UNITED STATES PATENT OFFICE.

JAMES W. BRYCE, OF BINGHAMTON, NEW YORK, ASSIGNOR TO INTERNATIONAL TIME RECORDING COMPANY OF NEW YORK, A CORPORATION OF NEW YORK.

SYNCHRONIZING-CLOCK.

1,310,783.

Specification of Letters Patent. Patented July 22, 1919.

Application filed September 24, 1918. Serial No. 255,417.

To all whom it may concern:

Be it known that I, JAMES W. BRYCE, a citizen of the United States, residing at Binghamton, in the county of Broome and 5 State of New York, have invented certain new and useful Improvements in Synchronizing-Clocks, of which the following is a full, clear, and exact description.

In a prior application filed by me, Serial 10 No. 235,813, filed May 21, 1918, I have shown and described a synchronizing clock system in which there are combined a master clock and one or more secondary clocks under the control of the former. One of the more 15 prominent features of this system consists in the means employed for maintaining the secondary clock or clocks in approximately perfect synchronism with the master clock, at least during the working hours when the 20 clocks are in use for the control of such means as time recording devices, between which, or even during such periods, there may occur interruptions in the supply of the more powerful currents required for the 25 operation of the system. The primary object of the invention was to dispense with a continuously dependable source of current, such as would be afforded by a storage battery or the like.

30 In the system in question, each secondary clock operated circuit controllers by means of which the said clocks were brought at certain times and for definite periods into such operative relations to the line circuit or a 35 line circuit running from the master clock, that by current transmitted over such circuit for definite periods by the master clock, the secondary clocks out of synchronism would be retarded or accelerated as the case might 40 be until by their retardation or advance they were brought into exact synchronism with the master clock, when the synchronizing circuits would be interrupted either by the master or secondary clocks and the latter 45 would thereafter run without control until such time as these circuits might be re-established.

The invention, subject of this application 50 is an improvement on such systems, and has to do solely with the means for retarding or for accelerating the secondary clocks to bring them, provided they be too fast or too slow, into exact synchronism with the master clock.

Generally stated this improvement consists in means for varying the length of the pendulum of a secondary clock if such device be used as its regulator, or the length of the hair spring, if such be the means employed for that purpose, at certain definite 55 periods, provided the clock be either too fast or too slow. For this purpose each secondary clock is provided with two circuit controllers which by the movements of such clocks are operated during certain predetermined periods to close a circuit from the master clock over which in certain fixed relation to correct time, current is transmitted. If one of the circuit controllers in a secondary clock, therefore, closes this circuit at the 60 instant when an impulse period established by the master clock begins or ends, then the master and that secondary clock are in synchronism and nothing occurs. But should this secondary clock circuit controller close 65 this circuit for a period overlapping that of a current transmitting period, there will be a certain flow of current through one or the other of such circuit controllers which will be utilized to increase or decrease the length 70 of the pendulum or hair spring, and thereby cause the secondary clock to slow down or speed up until by one or more such operations it is brought into exact synchronism 75 with the master clock.

80 In illustrating this invention I have shown diagrammatically merely such parts of the master and secondary clocks and circuits as are directly involved in the carrying out of the improvement, as all else is now 85 well known as a result of my previous work 90 in this connection.

Figure 1 is a side view of a pendulum 95 clock with means attached thereto for varying the length of the pendulum.

Fig. 2 is an enlarged detail view in elevation of such means.

Fig. 3 is a section view of the ratchet mechanism of the same.

Fig. 4 is a sectional view of the same 100 device.

Fig. 5 is a diagrammatic view showing the relation of the master to a secondary clock, and

Fig. 6 is a view of a modification of Fig. 2. 105

A designates the frame of a pendulum clock of the kind contemplated for the purpose of this invention. B the works thereof

and C the pendulum suspended by the usual flexible metallic strip D. The effective length of the pendulum is determined by the position of a bifurcated arm E which 5 closely embraces the metal strip D.

This arm extends from a threaded sleeve F on a correspondingly threaded spindle G, the sleeve being held against rotation by an arm H with an eye therein through which 10 passes a smooth fixed vertical rod K. The spindle G carries two ratchets I and J with teeth oppositely set, and with these ratchets engage the pawls L connected to the armatures M of two electro-magnets N, O. The 15 ratchets are so designed that without interference they will turn the screw G in opposite directions.

Magnet N is included in a branch of a circuit from the master clock, which in addition to the devices connected therewith in 20 that clock, contains a circuit controller P normally open but adapted to be closed by the raised portion of the periphery of a disk Q rotated by the secondary clock mechanism.

Magnet O is included in a branch of the same or a similar circuit which contains a circuit controller R, held normally open by a disk S, but allowed to close when one of 30 its members reaches a cut away portion in the periphery of said disk.

At predetermined intervals of definite length, a current is transmitted from the master clock over the line T. If this current 35 is received through the circuit controller P, it is broken up into impulses by the contacts U, rotated by the secondary clock, and the magnet N is operated and caused to move the ratchet wheel I step by step by such impulses and lowers the arm E to shorten the 40 pendulum. On the contrary, if the impulses are received by magnet O, the pendulum is lengthened, as the spindle G is turned in the opposite direction.

The operation in detail may therefore be 45 described as follows: Let it be assumed that from fifteen minutes of the hour until the hour, this period being selected merely for purposes of illustration, the master clock 50 sends a current into the line T by means to be hereinafter described. Let it also be assumed that at the hour, according to the hands of the secondary clock, the contacts R slip into the cut away portion of the disk 55 S. It is manifest, therefore, that if the secondary clock is exactly on time, the circuit controller R will be closed at the instant that the current flow from the master clock ceases, so that nothing will happen.

Should the secondary clock, however, be 60 fast, the contacts will drop into the cut away portion before the hour, or while the current is coming from the master clock. This current broken into impulses, then, until the 65 master clock stops sending current, will pass

through the magnet O and raise the sleeve F on the pendulum giving to the clock a slower rate.

A similar but opposite effect is produced by the circuit controller P. If the clock is 70 slow, the raised portion of the disk which should leave the contacts at exactly fifteen minutes of the hour will not permit these contacts to open at exactly that time, but will maintain them closed while current is 75 coming from the master clock and this results in shortening the pendulum by magnet N and giving to the clock a faster rate.

In practical operation, since the adjustment of the above described devices occurs 80 once each hour, the departure of any secondary clock from approximate synchronism is so slight that but few current impulses will pass through either magnet N or O. In case of protracted failure of current and the clocks get much out of synchronism, they are soon brought back into unison, if not entirely by one, certainly by a very few adjusting operations.

Instead of varying the length of the pendulum the same result may be accomplished by varying the length of a hair spring. In Fig. 6 this is indicated where a lever V is raised or lowered by an arm W on the prolongation of the spindle G and this operates 95 to vary the effective length of a hair spring X.

It will be understood that no means for winding the secondary clocks or performing other functions are illustrated, and that 100 no parts of the master clock are shown in detail, nothing in fact being illustrated in the drawings except the means for sending current over the circuit T for definite and predetermined intervals of time. Even these 105 means, being well known, are indicated diagrammatically only, as consisting of a disk Y with conducting segments on which bear brushes Z, that for a definite period, the disk being driven by the master clock, 110 maintain either a high or low point of a ratchet Z' opposite one of a pair of contacts X' in the line circuit.

I am aware that in the prior art provision has heretofore been made for advancing and retarding, using the latter term in a broad sense, the hands of a clock at any desired interval of time for maintaining such clock in synchronism with a master clock, but no means have been heretofore 115 proposed to my knowledge for providing for anything beyond substantially minute corrections, nor have any means such as I now propose been employed which take care of time inaccuracies of any extent.

Having now described my invention, what I claim is:—

1. In a clock system comprising an electric circuit, a master clock and one or more secondary clocks controlled thereby, the 130

combination in each secondary or controlled 5
clock of means for varying the length of the pendulum, circuit controllers adapted to be closed for giving periods of substantial
duration by and in definite relation to the
time as indicated by the hands of the controlled
clock, means in the master clock for connecting
to the circuit including said controllers a source of current for definite
10 periods of predetermined duration whereby, when the periods of closure in the secondary clock overlap that of the master clock, current will be directed through one or the other of said circuit controllers to the
15 means for lengthening or to the means for shortening the pendulum according to whether the secondary clock be too fast or too slow, and operate said means during the entire interval by which said periods over-
20 lap.

2. In a clock system comprising an electric circuit, a master clock and one or more secondary clocks controlled thereby, the combination in each controlled clock of elec- 25
tromagnetic ratchet and pawl devices, one for lengthening, and the other for shortening the pendulum, circuit controllers adapted to be closed for given periods of substantial duration by and in definite relation
30 to the time as indicated by the hands of the controlled clock, and means in the master

clock for connecting to the circuit including the said controllers a source of current impulses for definite periods of predetermined duration, whereby, when the periods of closure in the secondary clock overlap that of the master clock, impulses of current will be directed through one or the other of said circuit controllers to the ratchet device for lengthening, or to that for shortening the 40 pendulum according to whether the secondary clock be too fast or too slow, and effect the operation of said devices during the entire interval by which said periods overlap. 45

3. The combination with a secondary clock 45
of a spindle which by its rotation in opposite directions lengthens or shortens the pendulum, ratchets and pawls and electro-
magnets for operating said pawls and thereby turning the spindle in opposite direc- 50
tions, circuit controllers operated by the clock mechanism and adapted to be closed thereby for given periods, circuit connections and a device for developing impulses of current between the said controllers and the 55 electro-magnets, whereby current when received through a closed controller will be transmitted as impulses therefrom to the magnet connected therewith.

In testimony whereof I hereunto affix my 60
signature.

JAMES W. BRYCE.
